his attorney.

UNITED STATES PATENT OFFICE

RICHARD P. WINCKLER, OF LATONIA, KENTUCKY.

BOOKBINDING.

SPECIFICATION forming part of Letters Patent No. 694,593, dated March 4, 1902.

Application filed October 4, 1901. Serial No. 77,614. (No model.)

To all whom it may concern:

Be it known that I, RICHARD P. WINCKLER, a citizen of the United States of America, and a resident of Latonia, in the county of Kenton and State of Kentucky, have invented certain new and useful Improvements in Bookbinding, of which the following is a specification.

This invention relates to certain improvements in bookbinding, and has for its object to provide a binding of a simple and inexpensive nature adapted to impart increased strength and durability to the bound books, while presenting a degree of flexibility at the backs sufficient to permit of opening the books freely without danger of damage or undue strain upon the binding.

The invention consists in certain novel features of the improved binding, whereby certain important advantages are attained and the binding is made stronger and more durable and flexible, all as will be hereinafter fully set forth. The novel features of the invention will be carefully defined in the claims.

In the accompanying drawings, which serve to illustrate my improvements, Figure 1 is a perspective view showing a book bound according to my invention; and Fig. 2 is a fragmentary sectional view drawn to an enlarged scale and showing certain features of the improved binding to be hereinafter referred to, the plane of the section being indicated by the line *a a* in Fig. 3. Fig. 3 is a view showing the binding edges of the assembled signatures. Fig. 4 is an enlarged fragmentary section, showing the means for reinforcing the folded sheets at the binding edges. Fig. 5 is an enlarged sectional detail view showing a form of tape preferably employed in the improved binding.

In these views, 1 indicates the back of the book, and 2 2 indicate the sides thereof, while 3 indicates the body of the book. 4 4 indicate the first and last signatures, and 5 the intervening signatures, comprised in the body 3 of the book.

In preparing the signatures for sewing the outer sheets 11 of the first and last signatures 4 4 of the book are provided with reinforces 12 in the form of folded strips of muslin or other tough and flexible material secured along the lines of fold, as shown in Figs. 2 and

4, the stitches 8, by means of which these signatures are sewed in place, being passed centrally through these reinforces. Other reinforces 13 are also provided upon the first and last signatures 4 4, these latter reinforces being also in the form of strips of muslin or other tough and flexible material folded, as shown at 14, to produce two plies, which are 60 carried around the said signatures 4 4 at their binding edges, so that the folded part of each strip is held between one of the outer signatures 4 and the adjacent inner signature 5, as shown in Figs. 1, 2, and 3, the reinforces being glued or otherwise secured in position. The stitches 8 are also passed through the two plies of the reinforces 13, and the plies 15 and 16 of the reinforces are extended at the front and back of the book and are free from one 70 another, the outer ply 15 being of greater width than the inner ply 16, as clearly shown in Figs. 2 and 3. The inner plies 16 carry fly-leaves 18, as shown in Figs. 1 and 2, while the outer plies 15 carry the end sheets 17, the 75 said fly-leaves and end sheets being pasted along the edges of the plies, so that they are secured thereby to the first and last signatures 4.

In my improved binding tapes 6 are employed, extended transversely across the binding edges of the signatures, these edges being unsewed and the tapes resting against them along their flat sides. The ends 7 of the tapes 6 are made to project beyond opposite sides 80 of the body 3 of the book and are adapted for attachment to the sides 2 2 of the cover.

Each of the signatures 4 4 and 5 5 is held by the stitches 8 to the tapes 6, the said stitches being passed entirely around the tapes, as indicated in Fig. 3, so that the attachment of the signatures to the tapes is at a point behind the binding edges of the signatures, whereby greater flexibility is imparted to the binding, permitting the book to be opened to a flat form 95 without danger of straining the sewing.

For the tapes 6 I preferably employ a material in the form of a flattened woven tube, as indicated in Fig. 5, this material being more flexible than a strip of single-ply material of 100 equal strength, since the glue does not permeate both plies, and consequently does not impair the flexibility of the inner ply of the two-ply tape. The tape 6 being of consider-

able width also permit of accommodating themselves to strains upon the threads, so that the sewing is not liable to be broken when the book is opened in a flat form.

- 5 A strip or piece 9 of canvas or other stout material is glued or otherwise secured upon the body of the book outside the tapes 6 at the binding edges, the width of said strip or piece 9 being such as to permit the lateral parts 10 thereof to extend at the sides of the book to permit of attachment to the sides 2 2. In binding the book the reinforces 12 and 13 are first applied to the outer signatures 4 4, the fly-leaves and end sheets being secured by the reinforces 13 to said signatures, after which the several signatures 4 and 5 are assembled and sewed to the tapes 6 6 and the canvas sheet 9 is glued over the back of the book, as shown in Fig. 3. The boards 20 are then laid upon the sides of the book and lightly glued to the extended lateral portions 10 of the canvas strip 9, after which the cover-sheet is applied over the boards and back in a well-known way. The cover having been 25 completed upon the book is then torn away from the lateral portions 10 of the canvas strip 9, so that it may be stamped or printed as desired, after which it is again applied over the book, the portions 10 being securely glued 30 down upon the inner faces of the sides 2 and the ends 7 of the tapes 6 being also securely glued down on the portions 10, as shown in Fig. 2. The end sheets 17, together with the outer plies 15 of the reinforces 13, to which 35 said end sheets are attached, are then securely glued or pasted down upon the inner surface of the sides.

My improved binding, as above described, is of an extremely simple and inexpensive nature and is especially well adapted for use, since it imparts to the bound books increased strength and durability, so that the sewing is prevented from damage and the covers are prevented from being torn away from the 45 books. The improved binding also affords great flexibility, since it is possible to open the book to a flat form without danger of damage to or undue strain upon the sewing. The reinforces 11 and 13 at the front and back of 50 the book also give increased strength and flexibility, so that the first and last pages, which are commonly easily torn away from the binding, are securely held in place and a flexible connection is produced between the body of 55 the book and the sides 2 2, permitting extreme flexure of the said sides upon the book without damage to the binding.

It will also be obvious from the above description that the improved binding is capable of some modification without material departure from the principles and spirit of the

invention, and for this reason I do not wish to be understood as limiting myself to the precise form and arrangement of the parts herein set forth.

Having thus described my invention, I claim—

1. In a binding for books, the combination of signatures, a back, sides and reinforces each formed from a strip of material folded at its central portion to form two plies, the folded central portion of each reinforce being held between one of the outer signatures and the next adjacent inner signature and the two plies of said reinforce being superimposed and extended around the binding edge of the outer signature and one of said plies being secured upon the adjacent side, substantially as set forth.

2. In a binding for books, the combination of a back, signatures, sides and reinforces each formed from a strip of material folded at its central portion to form two plies, the folded central portion of each reinforce being held between one of the outer signatures and the next adjacent inner signature and the two plies of said reinforce being superimposed and extended around the binding edge of the outer signature and one of said plies being secured upon the adjacent side, and a fly-leaf secured upon the other ply of said reinforce, substantially as set forth.

3. In a binding for books, the combination of a back, signatures, sides, reinforces each formed from a strip of material folded at its central portion to form two plies, the folded central portion of each reinforce being held between one of the outer signatures and the next adjacent inner signature and the two plies of said reinforce being superimposed and extended around the binding edge of the outer signature, an end sheet secured upon one ply of each reinforce and a fly-leaf secured upon the other ply of each reinforce, substantially as set forth.

4. In a binding for books, the combination of a cover, signatures, tapes, each formed of a strip of flattened woven tubing extended transversely across the binding edges of the signatures and having its two plies movable one on the other at its central part, said strip being secured at its ends to the cover and stitches passed through the signatures and engaged with said tapes, substantially as set forth.

Signed at Cincinnati, Ohio, this 1st day of October, 1901.

RICHARD P. WINCKLER.
